LIGHT RAY AND MASSAGE THERAPY

Amos R. Marty, Marion, Ohio.

Application December 11, 1946, Serial No. 715,557

7 Claims. (Cl. 128—24.2)

1

This invention relates to light ray and massage therapy.

Among the objects of the invention is the provision of a manual device for the application of vibratory massages, infra-red light rays and heat to the human skin.

Another object is to accelerate the circulation of the blood, stimulate the muscular and vascular systems and build up the nerve energy of the human body.

A further object is the simplification and noiseless operation of the vibratory means and the mechanical and electrical control of the capacity of the infrared light and heat source.

Other objects and advantages will appear as the description proceeds. In the specification and the accompanying drawings, the invention is disclosed in its preferred form. But it is to be understood that it is not limited to this form; because it may be embodied in modifications within the spirit of the invention as we defined in the claims following the description.

In the one sheet of drawings:

Fig. 1 is a side elevation in vertical section on the line I—I, Fig. 2, of a device constructed in accordance with this invention.

Fig. 2 is a plan view from above of the same, with the cover omitted.

Fig. 3 is a fragmentary detail in vertical section on the line III—III, Fig. 2, showing the mechanical adjustment of the infrared ray and heat assembly.

Fig. 4 is a detail in vertical section of a modified form of massage member.

In detail the structure shown in Fig. 1, comprises the cylindrical body 1, open at the top and bottom and having the integral handle base 2 extending laterally from the body. The cover 3 closes the top of the body and the handle base 2 and is attached thereto by the screws, such as 4, threaded into the lugs such as 5, integral with the base 2 and the top of the body. The base has the transverse bridge 6 extending across the diameter of the body, and has the lugs 7, 8, extending outward therefrom.

The infra-red light and heat source comprises the lamp 9 having its base extending into the socket 10, wherein it is fixed by the bayonet connection such as 11. Such lamps are conventional in this art and have the upper portion of the parabolic glass silvered to reflect and concentrate the rays given off by an internal filament.

The socket 11 is fixed within the adjusting bar 12, having its opposite ends guided in the longi-

2

tudinal slots 13, 14, extending from the bottom of the body 1, up to the level of the bridge 6.

The spring latches 15, 16 are fixed to the underside of the bar 12, see Fig. 3, and extend downward and have the tapered and sharpened ends extending into the slots 13, 14, the inner edges of which they normally engage and lock the bar 12 and lamp 9 in selected position. These latches have the buttons 17, 18, extending through the slots 13, 14. When these buttons are pressed inward by the thumb and finger of the operator the latches are disengaged and the lamp may be longitudinally adjusted within the body 1.

The annular massage member 19 is mounted upon the lower ends of the legs 20, 21 of the U-shaped yoke 22, with the massage member axially aligned with the lamp 9. The lugs such as 23 on top of the massage member detachably engage in the sockets 24, 25 on the lower ends 20 of the legs of the yoke. A modified form of massaging member 19X is shown in Fig. 4, and may be substituted for the member 19 by inserting the lugs 23X into the sockets 24, 25.

The yoke 22 has the slotted central stud 26 fixed to the underside of the yoke and straddled over the center of the flat spring 27, to which it is welded or otherwise fixed. The opposite ends of the spring are likewise fixed in the split studs 28, 29 that are fixed to the lugs 7, 8, of the bridge 6.

The laminated iron core 30 is firmly mounted on the base 2 in substantial alignment with the yoke 22, within the handle and has the coil 31 surrounding the center pole 32 of the core. The iron armature 33 is welded or fixed on the leg 21 of the yoke, and extends into the handle with its free end aligned with the face of the center core 32, and normally spaced outwardly therefrom by the spring 27. The gap between the face 34 of the core and the armature is predetermined before the laminated core is screwed tight to the base 2. The vibrations of the armature 33 transmitted through the legs 20, 21, give a torsional oscillating effect to the massage member 19.

The electric circuit includes the incoming and outgoing wires 34, 35 from a source of A. C. current, not shown. The current flows in over the wire 34, through the coil 31 and back to the source over the wire 35. This energizes the laminated core which magnetically attracts the armature 33 to the face 32 of the core, against the tension of the spring 27, causing an oscillatory vibration of the yoke 22 on the center axis 26, which is transmitted to the massaging member 19. The amplitude of the vibration of the arma-

ture 33 may be mechanically adjusted by the screw 36 threaded in the side of the base 2. This adjusting screw has the rubber insert button 37, for silently contacting the armature. If no vibration is desired the screw 36 is turned inwardly until it jams the armature 33 against the face of the core 32. For a more delicate adjustment of the amplitude of the magnetic attraction the dampener 38 is provided. This consists of a laminated iron block interposed between the face 32 of the core and the inside surface of the side of the base 2. The dampener may be advanced across the face 32 by the stud 39, extending through a slot 40 in the base, against which it is set by the knurled nut 41 threaded on the stud. The dampener as shown is set for minimum vibration of the armature 33. By sliding the dampener out of contact with the face 32, maximum vibration is restored to the armature.

Lamps such as 9 are designed to operate on reduced voltage which may be controlled by a rheostat or more simply by shunt circuits, such as 42, 43, tapped into the coil 31 at appropriate points for conducting lower voltages to the filament of the lamp. These shunt circuits are selectively chosen by a single pole switch such as diagrammatically shown at 44. This switch mechanism is assembled on the inside of the body 1 at any convenient point and may be operated by the protruding button 45, within easy reach of the thumb of the operator, for varying the intensity and volume of infra-red rays emitted by the lamp 9. In this manner a range of voltages is available from sixteen to twenty volts, more or less, in accordance with the rating of the lamp 9.

In addition to the electrical variation of the lamp output just described, the lamp may be raised and lowered within the body 1, varying its proximity to the skin of the patient beyond the massaging member. This is accomplished by depressing the buttons 17, 18, between the thumb and finger of the operator, which releases the latches 15, 16, permitting the lamp mounting to be raised or lowered for meeting the light and heat therapy indicated by the patient's skin condition.

If it is desired to massage the skin without the application of the light and heat rays from the lamp 9, the switch button 45 is moved to open the switch at 44, which switches off the lamp without affecting the vibratory massage motive means.

If light and heat treatment is desired without massage the vibratory controls at 36 or 41 may be adjusted to stop the vibration of the armature 33, as previously described. The light emitted by the lamp 9 is concentrated by the reflector coating on the bulb above the filament and projected downwardly through the center opening in the annular massaging member 19.

Surplus radiations of heat from the lamp escape laterally through the slots 13, 14, and upwardly through the perforations 46 in the cover 3; which also permit escape of temperature arising from the coil assembly at 31. This escape of heat at 46 has an aspirating effect, drawing cold air into the handle at the opening 47, in the base 2.

The glass sealed lamp 9 is preferred as the source of infra-red rays and heat; but open hot filaments and similar sources may be substituted for the lamp. The fire hazard of such open filaments is practically eliminated by the enclosing body 1.

Various types of massage members are supplied as accessories. That shown in Fig. 1 is suitable for firm muscular areas, while the modification shown in Fig. 4 is adapted for deeper depression into facial, neck, abdominal and soft fatty tissues, for dissipating excess fat by massage and heat by more concentrated application on smaller areas. For sensitive or bony structures the face of the ring may be modified by omitting the knobby projections shown. Where heat therapy without massage is indicated and emollients are applied to the skin, the massaging member such as 19 may be omitted to give a wider spread of the heat rays from the lamp 9, through the open bottom end of the body 1.

While it is preferable to adjustably mount the lamp 9, or other heat source within the body 1, this source may be mounted externally on the body 1, in adjustable relation to the skin area beneath the heat source, without departing from the spirit of the invention.

Having fully described this invention and its mode of operation, what I claim and desire to secure by Letters Patent is:

1. A massaging device comprising a hollow body having a transverse bridge; a spring mounted on said bridge; a yoke mounted on said spring and having a projecting armature; massaging means on said yoke and projecting beyond said body; magnetic means on said body adjacent said armature for vibrating said yoke against the tension of said spring on a plane transverse to the axis of said body.

2. A massaging device comprising a hollow body having a transverse bridge; a flat spring having its opposite ends anchored to said bridge; a yoke mounted on said spring and having a projecting armature; massaging means on said yoke and projecting beyond said body; magnetic means on said body adjacent said armature for vibrating said yoke against the tension of said spring.

3. A massaging device comprising a hollow body having a transverse bridge and a lateral handle; a flat spring having its opposite ends anchored to said bridge; a yoke mounted on the central portion of said spring and having an armature projecting into said handle; massaging means on said yoke and projecting beyond said body; a magnetic core in said handle adjacent said armature; an electric circuit having a coil therein surrounding said core for vibrating said yoke against the tension of said spring.

4. A massaging device comprising a hollow body having a spring mounted therein; a yoke mounted on said spring and having a projecting armature; massaging means on said yoke and projecting beyond said body; an electric circuit having electro-magnetic means therein for vibrating said armature against the tension of said spring; an adjustable magnetic dampener overlapping the core of said electro-magnetic means for varying the amplitude of the magnetic attraction between said armature and core; and a therapeutic ray source in said circuit and adjustably mounted in said body relative to said massaging means.

5. A massaging device comprising a hollow body having a transverse bridge; a flat spring having its opposite ends anchored to said bridge; a yoke mounted on the central portion of said spring and having a projecting armature; massaging means on said yoke and projecting beyond said body; a magnetic core on said body adjacent said armature; an electric circuit having a coil therein surrounding said core for vibrating said yoke against the tension of said spring; and a thera-

peutic ray source adjustably mounted in said body relative to said massaging means and included within a shunt circuit interposed in said coil.

6. A massaging device comprising a hollow body having a lateral handle; and adjustable bar in said body and having latching means projecting through longitudinal slots in said body; a therapeutic ray source mounted upon said bar; a flat spring having its opposite ends anchored to said body; a yoke straddling said bar and mounted on the central portion of said spring and having an armature projecting into said handle; massaging means on said yoke and projecting beyond said body and aligned with said therapeutic ray source; and an electric circuit energizing said therapeutic ray source and having magnetic means therein for vibrating said armature.

7. A massaging device comprising a hollow body

having a transverse bridge; a flat spring having its opposite ends anchored to said bridge; a yoke mounted upon said spring and having massage means mounted thereon and projecting beyond said body; and means on said body for giving a torsional oscillating movement to said yoke and massage member on a plane transverse to the axis of said body.
